DIE FORMING AND TRIMMING APPARATUS.

1,337,796.

Specification of Letters Patent. Patented Apr. 20, 1920.

Application filed April 15, 1919. Serial No. 290,291.

To all whom it may concern:

Be it known that we, HERBERT J. SMITH, a subject of the Dominion of Canada, residing in the town of Kearney, county of Hudson, and State of New Jersey, and ERNEST P. EVERETT, a citizen of the United States of America, residing in the town of Flushing, county of Queens, and State of New York, have invented new and useful Improvements 10 in a Die Forming and Trimming Apparatus, of which the following is a specification.

The invention comprises a die forming and trimming apparatus, and the object is particularly to provide improved means for 15 making laminated barrel elements of the kind and under the process disclosed in United States Letters Patent No. 1,183,861 of May 23, 1916, issued to your joint petitioner Ernest P. Everett. The present apparatus 20 combines with the die members a set of spring-pressed trimming-knives laterally movable in a suitable holder, the knives and die being in bevel relation, together with means, as stout springs, for sustaining the 25 die above the knife-holder (or conversely) until the article has been formed or sufficiently compressed between the dies, whereupon the springs yield, permitting the sustained part to descend relatively to the 30 other and thereby causing the knives to shear off the edges of the stave at the requisite bevel and curvature. These and other features of the invention will become apparent as the specification proceeds, it being 35 understood that we do not limit ourselves to the precise form and application, which are susceptible of modification.

In the accompanying drawings:

Figure 1 is a view partly in side elevation and partly in central vertical longitudinal section; and

Fig. 2 is an end elevation.

A stave blank, made in accordance with our prior patent of forming a blank of a 45 plurality of layers with adhesive between, is placed between the elongated forming die members 1 and 2, the upper member 1 in this instance having a longitudinally and transversely concaved working face and the 50 lower member 2 having a correspondingly convexed face provided toward the ends with transverse ribs 3 to form the crozes. The upper forming member has apertured

margin flanges 4 for attachment to the upper part of a press, represented diagrammatically at 5. The lower forming member 2 is mounted in a frame or bed member 6, which is adapted to rest upon the bed of the press and constitutes a holder for trimming-knives 7 and 8, hereinafter described. It 60 will be understood that the relations might be reversed, the arrangement shown, however, being more advantageous.

The convex forming member 2 is connected to the knife-holder 6 with freedom 65 for vertical guided movement by means of posts 9 and 10 which rise from the base of the knife-holder to enter correspondingly formed sockets 11 and 12 in the die member, the sockets 9 being hollow and provided with 70 reduced apertures in their tops to receive and retain the heads of pins 13 projecting downward from the die member. Stiff sustaining springs 14 are interposed between the convex die member 2 and the knife-holder or, which amounts to the same thing, between the die member and the bed of the press upon which the knife-holder rests. The function of these springs is to hold the 75 die part and knife part in vertically separated relation against pressure while the stave A is being formed between the die members, after which the springs are overcome so that the die descends relatively to the knives. The heads of the pins 13 co-operating with the apertures in the posts 9 80 limit the separation of the die and knife-holder under the action of the springs.

The convex die member 2 is tapered or beveled downwardly, that is to say reversely 90 to the convexity of its working face, the long sides 15 being straight beveled and the short side faces or ends 16 being both downwardly beveled and transversely incurved. The 95 side and end faces of the concave die member 1 are also preferably beveled and curved in substantial continuation with the faces of the convex member, and, in order to insure alinement, means, represented by screws 17, may be provided for adjusting the knife-support 6 horizontally upon the bed of the press. In order to avoid injury to the edges of the knives, however, we propose to construct around the metal die member 1 a casting of wood or other soft material, and die 100 member 1 itself may be constructed of wood 105

or other soft material. The end knives 8 extend transversely across and beyond the ends of the die member 2, and are of substantially triangular cross-section, with 5 bases finished to slide upon finished surfaces 18 of the knife-holder 6 and their inner faces beveled substantially in conformity with the bevel of the end faces of the die member. These faces of the end knives and their top 10 cutting edges 19 are also transversely incurved to correspond with the opposed body faces. The knives thus positioned are pressed toward the die member by springs 20 interposed between the knives and abut- 15 ment portions of the knife-frame, where they are retained by pins 21. Additional horizontal guide pins 22 screwed into the knife-holder frame extend at their inner ends into guide sockets 23 in the backs of 20 the knives. The cutting edges of these knives may lie in horizontal planes, as shown.

The side trimming-knives 7 are similarly mounted and guided, 20^a being their springs and 21^a, 22^a the corresponding pins, and 25 their inner faces are straight-beveled to contact with the beveled sides of the die. The cutting edges 24 of these knives are upwardly curved from the ends to the middle, as seen in the side view, their arch, how- 30 ever, being somewhat flatter than the arch of the working surface of the convex die member 2. The side knives 7, it will be observed are included between the end knives 8, which are accordingly normally held 35 away from the end faces of the die, and the edges of the side knives are located above or in advance of the cutting edges of the end knives. The ends of the side knives against which the end knives rest are preferably 40 beveled as indicated in the drawing.

The operation will now be briefly described. The die and knives are normally sustained in the inactive or vertically extended relation seen in Fig. 1. In this condition the edges of the working surface of 45 the convex die member 2 are everywhere above or vertically spaced from the cutting edges of the knives. Consequently, when the upper part of the press is raised, carrying with it the die member 1, a blank can be 50 inserted between the die members without interference from the knives. Pressure is then applied and the die members compress and shape the blank and unite its layers, the 55 portion of the pressure transmitted through the blank being resisted rigidly or semi-rigidly by the springs 14, which do not yield until the stave or article has been completely or sufficiently formed to permit of the trimming 60 operation. The sustaining means then permits the die and knife parts of the apparatus to move relatively to each other in the direction of pressure, thus causing the knife edges to approach the projecting edges of 65 the article. In this movement the beveled

faces of the die and knives slide upon each other with a camming action, causing the knives to yield laterally in their holder against the pressure of their springs, so that their edges trim the four sides of the blank 70 in diverging diagonal directions. The edges of the side knives 7 come into action first, the cut beginning at the opposite ends and proceeding in a shearing manner toward the center. As the members 2 and 6 approach 75 each other the beveled and curved faces of the end knives 8 contact with the corresponding end faces of the die member 2, and immediately thereafter the edges of these knives encounter the extremities of the arcs 80 of the projecting ends of the stave, which as the movement proceeds are also trimmed with a shearing cut from both ends toward the center. The trimming of the ends of the stave takes place within the movement required 85 for the trimming of the sides, the relations being preferably such that the end cuts are completed slightly before the termination of the side cuts, though this may be varied. Thereafter the press may 90 be opened, the formed and trimmed article removed, and a new blank may then be inserted and the operations repeated. When pressure is removed, the die member 2 and the knife-holder 6 are automatically separated 95 by the springs 12 and the knives are automatically restored inward by their springs 20 and 20^a.

What we claim as new is:

1. Apparatus of the character described, 100 comprising a die including concave and convex forming members, a knife-support, yielding trimming-knives laterally movable in said support and having bevel-engagement with the die, and sustaining-springs between the die and knife-support.

2. Stave-forming and -trimming means, 110 comprising a die including elongated concave and convex forming members, a knife-support, laterally-movable spring-pressed trimming knives, the knives and die being beveled, and sustaining-springs between the die and knife-support.

3. In apparatus of the character de- 115 scribed, the combination of a die including concave and convex forming members, laterally-movable trimming-knives in bevel relation to the die, and means for sustaining the die and knives in inactive relation until the material has been formed between the 120 die members.

4. Apparatus of the character described, 125 comprising, in combination, concave and convex forming die members, a knife-support associated with one of said members, spring-pressed trimming-knives laterally movable in said support, said forming member and knives having co-operative bevel faces, and sustaining means for spacing the forming member and knife-support in in- 130

- active relation until the material has been formed between the forming members. 50
5. A device of the character described, comprising the combination of a die including elongated concave and convex forming members, laterally movable side and end trimming-knives in bevel relation to the sides and ends of the die, and means for sustaining the die and knives in inactive relation while forming pressure is exerted upon the material between the die members. 55
6. In a device of the character described, the combination of a die including concave and convex forming members, laterally movable trimming-knives about the die and in bevel relation thereto, certain of said knives being included between others and having their edges in advance, and means for temporarily sustaining the die and knives in inactive relation. 60
7. A device of the character described, comprising a die including elongated concave and convex forming members, laterally movable side and end trimming-knives in bevel relation to the die, the side knives being included between the end knives and having their edges in advance, and means for temporarily sustaining the die and knives in inactive relation. 65
8. A device of the character described, comprising a die including concave and convex forming members, a knife-support associated with one of said members, sustaining-springs interposed between said knife-support and member, and trimming-knives laterally guided in said support, the knives and die having beveled engaging faces. 70
9. A device of the character described, comprising a die including forming members, a knife-support, guide post connections between said support and one of the forming members, interposed sustaining-springs, and trimming-knives laterally guided in the knife-support and in bevel relation to the die. 75
10. In apparatus of the character described, the combination of concave and convex forming die members, spring-pressed trimming-knives in bevel relation to the 80
- convex die member, and means for sustaining said die member and knives in inactive relation while forming pressure is exerted upon the material between the members. 85
11. In apparatus of the character described, the combination of a die including two forming die members, a knife-support, a knife laterally guided in said support, and means for temporarily sustaining the knife and die in inactive relation, said knife and die having beveled coöperative surfaces, respectively convex and concave transversely to their inclination. 90
12. A stave-forming and trimming device, comprising a die including elongated concave and convex forming members, laterally movable side and end trimming-knives, means for temporarily sustaining the die and knives in inactive relation, the die and knives having co-acting faces inclined with respect to the direction of pressure and the end knives and faces of the die being in addition transversely incurved. 95
13. In apparatus of the character described, the combination of a die comprising two forming members and having beveled sides, and laterally movable trimming-knives associated with one of the members, the other die member being of relatively soft material. 100
14. A device of the character described, comprising a die including concave and convex forming members, transverse ribs provided on said convexed faced member, a knife support, yielding trimming-knives laterally movable in said support and having bevel-engagement with the die and sustaining-springs between the die and knife support. 105
- In witness whereof we have hereunto signed our names at New York city, in the county of New York and State of New York this 14th day of April, 1919. 90
